FLUID SUPPLY FOR DENTAL ENGINES

Richard W. Page, Chappaqua, N. Y.

Application September 13, 1946, Serial No. 696,360

10 Claims. (Cl. 32—23)

1

This invention relates to dental apparatus.

The general object of the invention is to provide an improved arrangement for leading fluid supply lines along a dental engine arm to a dental instrument.

With this and still other objects which will appear in the following full description in mind, the invention consists in the combinations and arrangements of parts and details of construction which will now first be fully described in connection with the accompanying drawing and then be more particularly pointed out in the appended claims.

In the drawing:

Figure 1 is an elevation view of a dental engine arm embodying the invention in a preferred form;

Figure 2 is an enlarged view of a portion of the apparatus of Figure 1 adjacent the hand piece;

Figure 3 is an enlarged view of a portion of the apparatus of Figure 1 adjacent the shoulder joint of the engine arm;

Figure 4 is a detail view looking in the direction of the arrow 4 of Figure 2 and showing a clip used for holding fluid supply lines at the hand piece;

Figure 5 is a sectional view taken longitudinally of one of the fluid supply lines and showing the relation thereof to the clip of Figure 4;

Figure 6 is a view looking in the direction of the arrow 6 of Figure 2, and showing a clip for holding the fluid supply lines at an engine arm joint; and

Figure 7 is a section taken on the line 7—7 of Figure 2, and showing details adjacent the joint of Figure 2.

In my previously filed applications, Serial No. 511,073, filed November 20, 1943, now Patent No. 2,420,338, for Dental apparatus, and Serial No. 671,784, filed May 23, 1946, for Dental instruments, I have disclosed apparatus for supplying air and water to a drilling instrument. The present invention is an improvement thereon, being concerned with the lead or arrangement of fluid supply lines along the engine arm and being applicable generally for the supplying of fluid at the hand piece or other drill instrument, for whatever purpose desired. The fluid line arrangement at the hand piece is shown in the latter application referred to, but not claimed therein.

Figure 1 shows a conventional engine arm supported upon a standard 1, only the upper portion of which is shown, it being understood that

2

the substructure supporting the same will be of the usual type. At the upper end of the standard 1 is an inverted U-shaped member or gooseneck 2, the motor 3 and arm section 4 fixed thereto, being pivotally supported at the point 5 in a terminal fork of the gooseneck 2. As will be understood, the entire arm assembly may be rotated about a vertical axis where the gooseneck 2 is supported by the standard 1. The engine arm also comprises a shoulder joint 6, a second arm section 7, an elbow joint 8, a third arm section 9, a wrist joint 10 and a fourth arm section 11, at the end of which the hand piece is mounted in the usual way. It will be understood that each of the joints 6, 8 and 10, provides for hinging (about axes perpendicular to the plane of the figure) so as to increase or decrease the angles between adjacent arm sections, and moreover, pivotal movement of the adjacent arm sections with relation to each other and about the arm section axes is provided for, as at the points 12 and 13. Each joint comprises a generally triangular hinge frame element 14 to which the adjacent arms are hingedly secured and on the faces of which a pair of pulleys 15 are carried by means of a shaft 16, the pulley shaft being located on the inside of the hinge. The motor 3 is provided with a drive pulley 17 and the hand piece 18 is provided with a driven pulley 19, a belt 20 being led around pulleys 17 and 19 and around the pulleys 15 as indicated in full lines in Figure 1, and in dotted lines in the other figures. The belt 20 is carried around all guide pulleys 15 so as to be at the back or outside of the hinges. The engine arm and belt lead as thus far described are well known and conventional, the present invention consisting in fluid supply line elements for attachment to such an engine arm and the manner of combining the same therewith.

As will be observed, each of the joints of the engine arm of Figure 1 is capable of being straightened out, or practically straightened out, so that the belt courses run substantially straight past the hinges. Bending the hinges further in the same direction would result in the belt leaving the pulleys, and the hinges are constructed to prevent such further bending. Accordingly, the belt is led along the outside or backs of the hinges at each joint and will remain on the guide pulleys at all times. While the belt courses are shown as parallel in the figure, it will be understood that when any of the joints is rotated with respect to another joint, about the axis of the engine arm section therebetween, the belt courses will no longer be parallel but will wrap

about the engine arm section, sliding smoothly thereon as is usual. The present invention provides a fluid supply line lead which will not interfere with the belt action, even if the engine arm joints are pivoted so as to wrap the belt courses on an arm section.

Flexible air and water supply lines 30 and 31 terminate at the hand piece, being fastened within a fitting 32 mounted thereon. This fitting preferably comprises a valve box, as fully described in my second application above referred to. The lines pass to either side of the hand piece and down through apertures 33 of a guide fitting 34 which has a large aperture 35 forming a ring for fitting over central elements of the hand piece and being pressed between elements 36 and 37 thereof, as shown. These hand piece elements are conventional and the manner of attachment of the fitting 34 will be apparent to those skilled in the art. A bushing 38 is inserted in each of the tubes 30 and 31 and has a somewhat expanded upper end, as indicated in Figure 5, which shows a section through the tube 30, where it passes through an aperture 33 in the fitting 34. The bushings 38 prevent the tubes from sliding backwardly through the apertures 33. Sufficient slack is provided to permit rotation of the fitting 32 relative to fitting 34, one or the other of the supply lines wrapping on the hand piece. A supply line may also be pulled slightly through the fitting 34 to accommodate an extreme rotation, but a definite minimum slack is insured at all times by the bushings 38.

The tubes 30 and 31 continue side by side to the wrist joint 10, where they pass between clip or guide elements 39 formed on a belt guard member 40 which has a recessed central portion fitting over the frame plate 14 of the joint and which is fastened to the frame plate 14, as by means of a screw 41. The guard plate 40 also has side flanges 42 at each side coming down over the pulleys 15 as indicated. A similar plate 40 is provided at the joint 8. Its mode of attachment and relation to the tubing being the same as in the case of the joint 10, it required no further description.

The fluid supply lines 30 and 31 are led along the arm section 1 to the inside of the shoulder joint 15, each of these lines passing through a coil spring 43 fastened to the first arm section 4 as by screws 44, and the lines 30 and 31 are then led along the first arm section 4, being held thereto by clips 45. The springs 43, tending to straighten out, serve as slack take-ups for the tubing, taking up any slack which may be created by placing the engine arm elements in their various positions during the use of the drill or other implement by the operator. As before noted, a definite limit on the slack take-up is provided by the bushings 38 at the hand piece, sliding movement of the tubing at the guides 41 being permitted. The fluid supply lines 30 and 31 continue around the U-shaped member 2 of the standard 1 and are then led in any convenient manner to sources of air and water or other fluid supply, not shown.

With the foregoing construction, provision is made for all the usual movements of the engine arm without interference between the drive belt and the fluid supply lines and without having loose supply lines around the engine arm, or creating an untidy appearance or interference with the operator.

The courses of the fluid supply lines between

the fitting 34 and the fitting 32 of the hand piece permit, as will readily be apparent, almost a full rotation of the fitting 32 with relation to the fitting 34, the courses of the tubing 30 and 31 merely wrapping the hand piece in one direction or the other and sufficient slack being provided for this purpose.

The hand piece may also be turned about the joint 13 without causing interference between the drive belt and the fluid supply lines, as the fluid supply lines will wrap adjacent the joint 13 while the belts extend diagonally in different directions as guided by the pulleys, so as not to engage the supply lines. If joint 10 is rotated relatively to joint 8, the fluid supply lines will wrap somewhat about the arm section 9, passing closest to or touching the same midway between the joints and at an angular location midway between the angles at which the joints are turned with relation to each other. Since the fluid supply lines are positioned approximately midway between the pulleys, the courses of the belt will remain to either side of the fluid supply lines and will come in contact with the engine arm section 9 rather than the supply lines, so that no interference with the operation is created.

When the section 7 is considered, it will be observed that the drive belt courses cross the arm section 7 in passing from the outside of the joint 6 to the outside of the joint 8. The fluid supply lines, however, do not cross the arm section in the position of the figure. When the elbow joint is rotated, in either direction, one belt course will be straightened out and the other will wrap, while the fluid supply lines will wrap to one side of the one course and inside the line of travel of the other, creating no interference.

What is claimed is:

1. In a device of the character described, a dental engine arm comprising a plurality of sections joined together for pivotal and hinging movement by wrist, elbow and shoulder hinges, guide pulleys carried by the hinges for guiding a belt along the arm sections and outside the hinges, a fluid supply line, means for attaching the fluid supply line to the engine arm inside the shoulder hinge and including a slack takeup, and means for attaching the fluid supply line outside the elbow and wrist hinges.

2. In a device of the character described, a dental engine arm comprising a plurality of sections joined together for pivotal and hinging movement by wrist, elbow and shoulder hinges, guide pulleys carried by the hinges for guiding a belt along the arm sections and outside the hinges, a fluid supply line, means for attaching the fluid supply line to the engine arm inside the shoulder hinge and including a slack take-up, and means for attaching the fluid supply line outside the elbow and wrist hinges and guiding them therearound outside and midway of the belt courses at the hinges.

3. In a device of the character described, the combination with an engine arm and hand piece of two fluid supply lines, means for guiding the fluid supply lines along the engine arm to the hand piece, a fitting for attaching the fluid supply lines to the hand piece, a second fitting adjacent the pulley end of the hand piece for guiding the fluid supply lines, the said fluid supply lines passing to opposite sides of the hand piece between the two fittings and having slack for permitting relative turning of the fittings, and means for preventing movement of the supply lines backwardly through the second said fitting.

75

4. In a device of the character described, the combination with an engine arm and hand piece of two fluid supply lines, means for guiding the fluid supply lines along the engine arm to the hand piece, a fitting for attaching the fluid supply lines to the hand piece, a second fitting adjacent the pulley end of the hand piece for guiding the fluid supply lines, the said fluid supply lines passing to opposite sides of the hand piece between the two fittings, and means for preventing movement of the supply lines backwardly through the second said fitting while permitting forward movement thereof to create slack and permit relative turning of the said fittings.

5. A device according to claim 4, in which the means for guiding the supply lines along the engine arm comprise guides permitting sliding thereof and a slack take-up for taking up slack in said lines between the shoulder joint of the engine arm and the said second fitting.

6. In a device of the character described, the combination with an engine arm and hand piece of two fluid supply lines, means for guiding the fluid supply lines along the engine arm to the hand piece, a fitting for attaching the fluid supply lines to the hand piece, a second fitting adjacent the pulley end of the hand piece and having apertures for guiding the fluid supply lines, the said fluid supply lines passing to opposite sides of the hand piece between the two fittings and containing bushings for preventing movement backwardly through the said aperture, whereby a predetermined minimum slack for permitting relative turning of the fittings is provided.

7. In a device of the character described, the combination with an engine arm hinge having belt guide pulleys on its faces, of a fluid supply line guide member fastened to the back of the hinge for holding fluid supply lines outside and midway of the guide pulleys.

8. In a device of the character described, the combination with an engine arm hinge having belt guide pulleys on its faces, of a fluid supply

line guide member fastened to the back of the hinge for holding fluid supply lines outside and midway of the guide pulleys and permitting sliding movement of the supply lines.

5 9. In a device of the character described, an engine arm section having wrist and elbow hinges according to claim 7 on each end thereof and embodying provision for pivotal movement of the said hinges with respect to each other about the engine arm section axis, whereby when the said hinges are so pivoted the fluid supply lines will wrap upon the engine arm section midway between the belt courses and without coming between either of the belt courses and the engine arm section.

10 15 20 25 30 35 40 In a device of the character described, an engine arm section having an elbow hinge according to claim 7 at one end thereof and a shoulder hinge at the other end thereof, pulleys on the faces of the shoulder hinge, belt courses led over the outside of the pulleys on both said hinges and crossing the engine arm section when in parallelism, and fluid supply lines carried by the guide member of the elbow hinge and attached to the inside of the shoulder hinge, whereby when the hinges are pivoted with relation to one another about the engine arm section axis, the fluid supply lines will wrap upon the engine arm section without coming between the engine arm section and the belt course which wraps thereon and the fluid supply lines will lie inside the belt course which moves toward parallelism with the engine arm section during such pivotal movement.
